UNITED STATES PATENT OFFICE.

LELA E. ALDERSON, OF CLAREMORE, OKLAHOMA.

CHURN.

Application filed August 21, 1928. Serial No. 301,051.

This invention relates to an improved butter churn especially constructed for use in association with a clothes washing machine.

More specifically stated, the invention is characterized by a churn having a rotary adapter plate provided with a power take-off coupling designed to fit upon a gyrator shaft in the tub or casing of a conventional type of clothes washing machine.

10 The principal purpose is to utilize the motive power of a household clothes washing machine to actuate a butter churn, by constructing the butter churn to function as a substitute for the usual gyrator.

15 The particular features and relative association and arrangement of details will become more readily apparent from the following description and drawings.

In the drawings;

20 Figure 1 is a view in section and elevation showing a known type of clothes washing machine, having the gyrator removed and the improved butter churn substituted therefor.

25 Figure 2 is a vertical sectional view through the improved churn per se.

Figure 3 is a fragmentary view of a part of the lid or cover for said churn.

Figure 4 is a special cover fitting.

30 Figure 5 is an elevational view of the dasher agitator removed from the can.

Figure 6 is a top plan view of Figure 5.

Figure 7 is an enlarged detail view, taken on the plane of the line 7—7 of Figure 6.

35 Figure 8 is a top plan view of the rotary adapter plate.

Considering now the specific details and referring to them by numerals and particularly to Figure 1, it will be observed that it illustrates conventional or known types of clothes washing machine, which includes a supporting leg structure 9, a tub 10, wringer 11, and an electric motor drive for the gyrator (not shown).

40 This drive embodies an electric motor 12, a power belt 13, having an operating connection with a crank shaft 14, which in turn has operating connection with a reciprocating pitman or rack bar 15. The pitman has operating connection with the pinion 16, on the gyrator shaft 17, journaled in a bearing in the bottom of the tub or casing 10. The shaft 17 is provided with a key which has separable connection with a coupling on the bottom of the gyrator (not shown).

45 55 As before stated, the gist of the invention is predicated upon the idea and means where-

by the gyrator can be removed and an improved butter churn substituted therefor to receive its power from the electric motive power of the washing machine.

60 In Figure 1, the churn is generally designated by the reference character 18, where it is shown having operating connection with the shaft 17. Referring to Figure 2, it will be seen that the churn comprises an open top 65 cylindrical container 19, whose base 20 is equipped with marginal depending supporting legs 21, and a central socket 22. The legs 21 are disposed within the upstanding annular rim 23, carried by a disc like adaptor 70 plate 24. On the center of the bottom side of the adapter plate is a depending coupling and driving sockets 25, having a keyway 26. Obviously, this coupling 25 corresponds in construction with a similar coupling such as 75 is found at the bottom of the gyrator. Hence it is simply slipped down over the key equipped shaft 17 as shown in Figure 1. The marginal portion of the adaptor plate is formed with elongated slots 27 accommodating 80 the headed lower ends of the retaining rods 28. The upper ends of these rods are releasably connected by thumb nuts 29 with the bifurcated portions of retaining brackets 30, on the container.

85 The cover for the container comprises a pair of half sections 31 and 32, of appropriate construction, having external handles or knobs 33. A special fitting 34 is carried by the section 32. This comprises a polygonal 90 shaft pocket 35, and spaced attaching arms 36. The meeting edges of the sections 31 and 32 are notched to accommodate the sockets 35, and this arrangement allows the sections 31 to be removed while the section 32 95 is in place as shown in Figure 2.

Located within the container 19 is a cream dasher. This embodies a shaft whose upper end portion 37 fits into the socket 35, and whose lower end portion 38 fits into the aforesaid socket 22 in the base. Mounted on the shaft is a hub 29 carrying twisted horizontal blades 40 and upper and lower radial arms 41, provided with retaining channels 42 for vertical blades 43.

100 110 In practice, the container with the dasher therein and the covering plate is assembled on the adapter plate as shown in Figure 2, and the clamping bolts 28 are put in the position here shown to maintain the parts assembled. Then the complete device is ready for insertion in the tub 10, to take the place of the

gyrator which has now been removed. The churn is simply coupled to the gyrator shaft 17 and the motor set into operation, whereby to actuate the churn and to permit the rapid 5 making of cream into butter.

It is thought that the advantage, construction, operation of the invention will be quite clear when considering the description in connection with the drawings. Therefore, 10 a more lengthy description is deemed unnecessary.

Minor changes in the shape, size, and materials coming within the field of invention claimed may be resorted to, in actual practice, if desired.

I claim:

1. A butter churn of the class described adapted for use in association with a gyrator shaft in a clothes washing machine comprising 20 an adaptor plate having a central shaft coupling socket on its bottom, having an annular upstanding rim near its periphery and having radial slots on the outside of said

rim, a container having supporting legs resting upon the adapter plate and confined within said rim, a dasher in said container, brackets on the container, and clamping bolts connected with the brackets and with the slotted peripheral portions of the adaptor plate.

2. A butter churn adapted to serve as a substitute for a gyrator in a clothes washing machine comprising an adapter plate having a coupling for releasable connection with the gyrator driving shaft, said plate also having an annular retaining rim, and a container provided with supporting feet resting upon the adaptor plate and confined within said rim, clamping bolts connected with the container and adapted plate, a dasher located in 40 said container, and a sectional cover for the container provided with a fitting with which the dasher shaft is connected.

In testimony whereof I affix my signature.

LELA E. ALDERSON.
